UNITED STATES PATENT OFFICE.

FELIX H. CRAGO, OF SAPPINGTON, MONTANA.

PUMP.

Specification of Letters Patent. Patented Sept. 30, 1919.

1,317,358

Application filed October 31, 1917. Serial No. 199,528.

To all whom it may concern:

Be it known that I, FELIX H. CRAGO, a citizen of the United States, residing at Sappington, in the county of Gallatin and State of Montana, have invented a new and useful Pump, of which the following is a specification.

The subject of this invention is a pump of the rotary type, and the objects of the invention are, first, to provide a rotary piston for the pump, second, to provide means for properly positioning the piston at the different stages of its rotation, third, to provide a rotor for a pump, fourth, to provide 15 a simple, durable and efficient pump.

With the foregoing and other objects in view which will appear as the description proceeds, the invention resides in the combination and arrangement of parts and in 20 the details of construction hereinafter described and claimed, it being understood that changes in the precise embodiment of the invention herein disclosed, can be made within the scope of what is claimed, without departing from the spirit of the invention.

A practical embodiment of the invention is shown in the accompanying drawing wherein:

30 Figure 1 is a view in side elevation of the pump with the near side of the casing removed;

Fig. 2 is a vertical longitudinal section;

35 Fig. 3 is a detail view of the rotor.

Referring to the drawing by numerals of reference:

The casing is the usual drum shaped casing 1, divided longitudinally and provided with radially disposed apertured lugs 2 40 adapted to receive bolts or the like by which the casing is clamped together.

Apertured feet 3 depend from the casing for the purpose of supporting the same and to permit the pump to be fastened to a plat- 45 form, bed-plate or the like. An intake pipe 4 and an outlet pipe 5 are provided and are preferably integral with the casing. These pipes may be threaded as shown, to permit the pump to suitably connect in the pipe 50 line.

Opposed cylindrical extensions 6 are formed eccentrically of the casing 1 and provide journal boxes for supporting the rotor of the pump. Formed centrally of

the head of one of the extensions 6 is an 55 outwardly projecting boss 7 which is apertured or bored as shown to form a stuffing box or packing space 8.

Each half of the casing 1 is formed with an annular recess which join when the sections are clamped together to form an annular groove 9. A cam track 10 is clamped within the groove 9 for a purpose herein-after set forth, the surface of the cam track being flush with the inner surface of the 65 casing except at that portion, 10', at the upper part of the casing, which portion projects inwardly.

Within the extensions 6 turn the journals 70 or trunnions 11 of the rotor. The rotor consists of the cylinder 12 in which is formed the central annular groove 13, and through which is cut the diametrically disposed longitudinal slot 14. The slot 14 is formed with central opposed offsets 15 as shown. One 75 journal or trunnion of the rotor may be apertured, as indicated at 16, for the reception of the end of a drive shaft.

The piston 17 is mounted in the slot 14 of the rotor with a close sliding fit, and has a 80 longitudinal rib 18 centrally disposed on each face thereof and adapted to enter the offsets 15. As will be readily understood, contact of the edges of the piston 17 with the end walls of the slot 14 will serve to guide 85 the piston in its reciprocation through the slot and prevent sidewise tilting thereof, such positioning and movement of the piston being rendered doubly certain by the ribs 18 held in the offsets 15.

90 Each end of the piston 17 has formed therein a central slot which extends transversely of the edge and in which is mounted in any suitable manner a roller 19. The rollers 19 engage the cam track 18 so as to reduce friction of the parts.

95 The operation of the device is as follows: The pump is connected in a suitable pipe line leading from a suitable source of liquid supply to the pump through its intake 4, and 100 from the pump through its outlet 5 to a suitable liquid receiver. A shaft, geared in any suitable manner to a source of power, is connected to the rotor and rotary motion im- 105 parted.

As the rotor travels from the position shown in Fig. 1 in the direction of the arrow, liquid is drawn, by the suction of the piston,

through the intake, while liquid ahead of the piston is forced by the forward movement of the piston, through the outlet 5.

When the piston first starts from the position shown in Fig. 1, the upper edge of the piston is within the slot of the rotor and ceases to be in contact with the casing until the lower edge of the piston has traveled sufficiently to bring its roller 19 in contact with the cam 10' of the cam track 10. The cam face 10' gradually forces the piston 17 to the position shown in Fig. 1.

As will be readily understood, while the upper edge of the piston is within the slot 15 of the rotor, water is free to flow to the casing without any back pressure from the upper portion. It will also be seen that the cam face is so located as to gradually release pressure on the outgoing water and avoid the 20 shock which would be caused by the trapped water were the piston brought to its vertical position with the upper edge in contact with the casing.

Having thus described the invention, what

is claimed as new and sought by Letters 25 Patent, is:

1. A pump, comprising a casing, a cam track within the casing, a rotor within the casing and mounted eccentrically thereof, said rotor formed with an annular groove 30 for the reception of the cam track, and a piston sliding in the rotor and reciprocated by the cam track.

2. A pump, comprising a casing, a cam track in the casing, a rotor within the casing, said rotor formed with an annular groove for the reception of the cam track and with a diametrically disposed longitudinal slot, and a piston sliding in the slot and reciprocated by the cam track.

40 In testimony that I claim the foregoing as my own, I have hereto affixed my signature in the presence of two witnesses.

FELIX H. CRAGO.
